(57) **CLAIM**

The ornamental design for a wheel, as shown and described.

DESCRIPTION

FIG. 1 is a perspective view of a wheel showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof;

FIG. 7 is a bottom view thereof; and,

FIG. 8 is a partial enlarged view showing the part indicated by reference numeral 8 in FIG. 1.

The broken (dashed) lines show portions of the wheel that form no part of the claimed design. The dot-dashed broken line in FIGS. 1 and 8 shows the boundary of the enlarged view and forms no part of the claimed design.

1 Claim, 8 Drawing Sheets
